UNITED STATES PATENT OFFICE.

WILLIAM MURRAY MORTON, OF DARVEL, SCOTLAND.

DESIGN FOR A CARPET.

40,580.

Specification for Design. Patented Mar. 15, 1910.

Application filed January 21, 1910. Serial No. 539,435. Term of patent 3½ years.

To all whom it may concern:

Be it known that I, WILLIAM MURRAY MORTON, a subject of the King of Great Britain, and resident of Hastings Square, Darvel, Ayrshire, Scotland, have invented a new, original, and ornamental Design for Carpets, of which the following is a specification, reference being had to the accompanying drawings, forming a part thereof.

The figure is a plan view of a portion of a carpet embodying my new design.

The design comprises a border the main feature of which is a treatment of rose groups placed on a band composed of trellis sprigs and a ground filling formed of lattice work.

I claim—

The ornamental design for a carpet, as shown and described.

WM. MURRAY MORTON.
